UNITED STATES PATENT OFFICE.

PAUL ARBON, OF TULSA, OKLAHOMA.

ROPE-CLAMP.

1,083,478.

Specification of Letters Patent.

Patented Jan. 6, 1914.

Application filed December 26, 1912. Serial No. 738,669.

To all whom it may concern:

Be it known that I, PAUL ARBON, residing at Tulsa, in the county of Tulsa and State of Oklahoma, a citizen of the United States, have invented or discovered certain new and useful Improvements in Rope-Clamps, of which improvements the following is a specification.

In drilling gas and oil wells, the movement of the drill is effected by a walking beam or other suitably reciprocating means, which is connected to the rope extending down into the well by a temper screw and clamps. In addition to the drill other tools for straightening and cleaning the well must be connected to the operating means from time to time. As the drill and the parts connected thereto are much heavier than the other devices it is desirable to use smaller ropes for the sand pumps, etc., than is required for the drill and the parts connected thereto. The clamps heretofore used have grooves for the large or drill rope, and hence such jaws must be removed and others substituted when smaller ropes are used.

The invention described herein has for its object the provision of jaws having a plurality of grooves varying in size thus permitting of the same jaws being used in connection with the various tools or implements used in drilling a well.

The invention is hereinafter more fully described and claimed.

In the accompanying drawing forming a part of this specification, Figure 1 is a top plan view of a clamp having my improvements applied thereto; Fig. 2 is a side elevation of one of the parts of the clamp, and Figs. 3 and 4 are detail views of one of the removable jaws.

The clamp consists of two parts or members 1 pivotally connected at one end and provided at their opposite ends with suitable means whereby said parts can be drawn together. A suitable construction for this purpose consists of a threaded rod 2 so pivoted to the end of one of the parts 1, that it can be swung into and out of a notch in the

other part, and a nut 3 mounted on said rod and adapted to bear against both portions forming the side walls of the notch in the second member. Each part or member is provided with suitable means as the links 4, whereby it may be connected to the temper screw. The inner faces of the parts or members are recessed for the reception of the jaws 5 in both sides of which are formed grooves 6 varying in transverse dimensions for the reception of different sides as are required in drilling wells. It has been found that the grooves in clamps are rapidly worn in use, and by forming them on an easily removable portion of the clamps only such part requires replacement when the grooves are worn. And further by forming these renewable parts with a plurality of grooves adapted to engage ropes varying in diameter, the several operations involved in drilling can be carried without any change of clamps or jaws. As clearly shown, the rope holding grooves are formed in both faces of the removable jaw, which is provided at its upper end with lugs 7, which extend into notches 8 in the side walls of the parts or members 1, so as to retain the jaws in position in the recesses. While not essential, it is preferred that the notches should be made with an angular extension into which the lugs may pass when being placed in position, so that the jaws will be held securely in their recesses. The lugs on the jaws and the notches in the side walls of the recesses should be so arranged that when the lugs are in position in the notches, the jaws will bear firmly against the back walls of the recesses. As is well known in the art, the grooves of the jaws are not a complete semi-circle, but have a depth less than half the diameter of the rope to be gripped so that the jaws can so firmly clamp the rope that the latter cannot slip through them during the drilling operation.

I claim herein as my invention:

A rope clamp having in combination two parts or members pivotally connected at one end, and having recesses formed in their inner faces, said recesses having their side

22
walls notched, means for drawing the parts or members together, and reversible jaws having grooves of different transverse dimensions in both faces, and provided with 5 lugs adapted to engage said notches in the side walls of the recesses of the parts or members.

In testimony whereof, I have hereunto set my hand.

PAUL ARBON.
